US0D1107920S

(12) **United States Design Patent** (10) **Patent No.:** **US D1,107,920 S**
(45) **Date of Patent:** **** Dec. 30, 2025**

(54) **TOURNIQUET**

(71) Applicants: **Benjamin Latham Griffith**, Salt Lake City, UT (US); **Arrius Lee Sorbonne**, Salt Lake City, UT (US)

(72) Inventors: **Benjamin Latham Griffith**, Salt Lake City, UT (US); **Arrius Lee Sorbonne**, Salt Lake City, UT (US)

(**) Term: **15 Years**

(21) Appl. No.: **29/820,619**

(22) Filed: **Dec. 22, 2021**

(51) LOC (15) Cl. **24-02**

(52) U.S. Cl.

USPC **D24/169**

(58) **Field of Classification Search**

USPC D24/143, 145, 147, 169, 187; D8/356, D8/383

CPC A61B 17/1327; A61B 17/1322; A61B 17/1325; B63B 35/7933; B63B 2035/794

See application file for complete search history.

(57) **CLAIM**

The ornamental design for the tourniquet as shown and described.

DESCRIPTION

FIG. 1 is a top oblique view of the tourniquet showing our new design;

FIG. 2 is a left side view thereof;

FIG. 3 is a right side view thereof;

FIG. 4 is a top plan view thereof;

FIG. 5 is a bottom plan view thereof;

FIG. 6 is a back elevational view thereof; and,

FIG. 7 is a front elevational view thereof.

The broken lines illustrate portions of the tourniquet that form no part of the claimed design.

1 Claim, 6 Drawing Sheets
